UNITED STATES PATENT OFFICE.

JAMES G. BOYD, OF JACKSONVILLE, FLORIDA.

TOP FOR SQUARE HAMPERS.

1,409,820.

Specification of Letters Patent. Patented Mar. 14, 1922.

Application filed June 28, 1921. Serial No. 481,045.

To all whom it may concern:

Be it known that I, JAMES G. BOYD, a citizen of the United States, residing at Jacksonville, in the county of Duval and State of Florida, have invented certain new and useful Improvements in Tops for Square Hampers, of which the following is a specification.

In the drawing,

10 Figure 1 is a perspective view of the hamper partially broken away, equipped with one of my improved tops.

Figure 2 is a vertical sectional view of Figure 1.

15 Figure 3 is an enlarged detail top plan view.

Figure 4 is a detail sectional view of the hamper top.

On account of the high cost of labor it 20 is necessary to reduce, as far as possible, the cost of manufacture of hampers which I use for shipping fruits, vegetables and the like, but at the same time it is necessary to preserve the strength of the hampers 25 to resist the rough usage to which they are subjected in transportation in order that the contents of the hamper may not be injured.

The object of my invention is to provide 30 a simple, substantial and cheap type of top for square hampers, which will rigidify the hamper at the top, thereby sustaining the hamper against crushing when packed for transportation in a car or on a truck or wagon.

35 A further object of my invention is to provide a simple but efficient fastening to secure the top firmly to the hamper;

And with these and further objects in view my invention consists of the parts and 40 combination of parts as will be hereinafter more fully set forth.

The reference numeral 1 designates a hamper of approved construction, the vertical slats 2 of which are provided with wire 45 hoops 3 which hoops are secured by means of the staples 4, the top portions of the slats being suitably nailed, or otherwise secured, to the cleats 5, which cleats project into the hamper from the sides.

50 Around the top and at the outside of the hamper are secured strips 6, which have between the adjacent ends thereof on each side of the hamper, a space 7. A wire hoop 8 is secured around the outer face of the top 55 of the hamper by means of staples 9, said

wire hoop overlying the strips 6 as shown in several views of the drawing.

My improved top consists of one or more pieces of veneer, preferably two pieces 10 and 11, which veneers are secured together 60 by means of stitching, nailing, or by staples, so as to make a comparatively thick rigid cover. Secured at diametrically opposite sides of the under face of the cover are two cleats 12, which cleats are spaced from the 65 extreme outer adjacent edges of the cover as more clearly shown in Figure 4, so that these cleats will fit inside of the hamper next to the hamper top cleats 5 so as to form a brace to the top of the hamper, thereby making the top of the hamper stronger and reducing the chances of the top of the hamper collapsing or breaking incident to rough usage in transportation.

70 In order to quickly and securely fasten 75 the top of the hamper to the hamper I secure wires 13 and 14 to the top hoop 8 of the hamper, one end of the wire fasteners 13 and 14 being firmly secured more or less permanently to the hoop 8, as clearly shown 80 in Figure 2, while the body of the wire is passed over the top of the hamper and its free end secured temporarily, but securely to the hoop 8 at the diametrically opposite side of the hamper, as clearly shown at the 85 left hand side of Figure 2.

The wire 14 is similarly secured at one end to the hoop 8 and passed across the top of the hamper, crossing the wire 13, and its free end secured similarly to the diametrically opposite side of the hamper, both connections of the wires 13 and 14 to the hoop 8 being within the space 7 between the adjacent ends of the strips 6, as clearly shown 90 in the drawing.

95 Certain details of construction shown in the drawings may be changed without departing from the scope of the invention as defined in the claims.

What I claim is:

100 1. The combination with a hamper having cleats secured to the vertical sides inside thereof and at the top of the hamper, strips secured to the outer face of the hamper in line with said cleats, adjacent ends of said strips being spaced from each other, a wire hoop secured around the top of the hamper over said strips, fastening means for the top for said hamper; said fastening means comprising two strands of wire, one end of each 105

110

strand being permanently secured to said hoop within the space between said strips, while the other end of the respective wires is adapted to be temporarily secured to the hoop at a point diametrically opposite the point of permanent attachment of the wires, said wires adapted to overlie the cover for the hamper.

- 10 2. The combination with a hamper having cleats secured to the vertical sides inside thereof and at the top of the hamper, strips secured to the outer face of the hamper in line with said cleats, adjacent ends of said strips being spaced from each other, a wire
15 hoop secured around the top of the hamper over said strips, fastening means for the top for said hamper; said fastening means com-

prising two strands of wire, one end of each strand being permanently secured to said hoop within the space between said strips, 20 while the other end of the respective wires is adapted to be temporarily secured to the hoop at a point diametrically opposite the point of permanent attachment of the wires, said wires adapted to overlie the cover for 25 the hamper; said cover comprising a main body adapted to close the top of the hamper and cleats spaced from the outer edge of said cover and depending therefrom and adapted to fit into the hamper next to the top cleats 30 of the hamper.

In testimony whereof I affix my signature.

JAMES G. BOYD.
